EARL H. SHERBONDY, OF CLEVELAND, OHIO.

METHOD AND APPARATUS FOR PRESSURE DIE-CASTING.

1,377,226.

Specification of Letters Patent.

Patented May 10, 1921.

Application filed May 14, 1918. Serial No. 234,561.

To all whom it may concern:

Be it known that I, EARL H. SHERBONDY, a citizen of the United States, residing at Cleveland, in the county of Cuyahoga and 5 State of Ohio, have invented certain new and useful Improvements in Methods of and Apparatus for Pressure Die-Casting, of which the following is a specification.

This invention relates to a method of and 10 apparatus for casting any kind of molten material, such as ordinary metals, as well as other materials which are susceptible of being cast, such as bakelite. More particularly the invention comprises a method and 15 means of pressure die casting, that is to say, one in which the metal is projected into and held in the die under pressure, until it is sufficiently cool to be removed.

The particular object of the invention is 20 to utilize centrifugal force as the force which presses the molten mass into the die and holds it there until cool. To this end the die is adapted to be rotated at high speed, and the molten mass is fed to said 25 die, so that it is practically instantaneously projected into the die, and held there under a pressure dependent upon the specific gravity of the metal that is being cast, and the speed of rotation of the die.

30 This method of casting presents this advantage:—Since the mass of molten material is much heavier than any small bubbles of air or other gas that may be caught by the molten mass on its way to the die, or 35 which may be present in the molten mass, the centrifugal force will carry this heavier metal as far away from the axis of rotation as possible, which will result in the relative movement of all of these small bubbles of 40 gas inwardly, thus giving a dense casting.

Another object of the invention is to provide suitable cooling means for the die, such cooling being necessary in order to prevent the die from becoming so hot that the molten 45 mass being cast therein will fuse thereto.

Another object of the invention is to provide means to cause forced circulation of the cooling medium over the outside face of the die, in order to provide a reliable and efficient cooling action.

Other objects and advantages will appear as the description proceeds.

Referring now to the drawings which are diagrammatic, Figure 1 is a vertical sectional view of the apparatus embodying my

invention, and Fig. 2 is a section on the line 2—2 of Fig. 1.

In Fig. 1, the upper and lower die-forming elements 1 and 2 coöperate to define a die space 3, which space 3 is intended to be 60 filled with the metal that is being cast to form the finished casting, and is accordingly cut from the die-forming elements 1 and 2 to define a space of the desired shape.

These elements 1 and 2 are circular in 65 shape, and are intended to be operated at a high rate of speed. The box-like casing 4, provided with a top 5, is arranged around the die, the top 5 being formed with a suitable ring 6, and packing gland 7, for the 70 proper mounting of the upper part of the element 1, while the casing 4 is provided with an aperture 8 for the passage of the shaft 9 of the die-forming element 2. The shaft portion 9 may be integral with part 2. 75 A flange 9', integral with the shaft 9, and a packing gland 10 coöperate with the shaft 9 to provide a tight joint before the shaft 9 passes out of the box 4. Shaft 9 is mounted in a suitable step bearing 11, and is rotated 80 at high speed by any suitable means, such as the pulley and belt 12.

The molten material is fed to the die through a vertically arranged funnel element 13, which is held stationary in a 85 suitable support 14, and passes inwardly through the packing gland 7, and through the upper part 15 of the die-forming element 1, and opens into the space 16 between the die-forming elements 1 and 2. 90

The lower die-forming element 2 may be provided with a conical projection 17, arranged concentrically with respect to the funnel element 13. The funnel element 13 may be lined with a refractory lining 13'. 95 It should be noted that the space 16 is in direct communication with the several spaces 3 forming the mold.

The parts 1 and 2 of the die may be offset as at 18, to aid in proper positioning of the 100 two elements, and may be further held together by screws or bolts 19, and a ring 20.

It is necessary to keep the elements 1 and 2 comparatively cool in order to prevent the molten mass that is being cast from fusing 105 therewith. To this end the box 4 is filled with some cooling medium, such as air, water, oil or molten lead, for example, depending upon the temperature at which it is desired to keep the die. In order to as- 110

sure intimate contact between this cooling medium and the outside surfaces of the die, the cooling medium may be kept under fairly high pressure by a pump 21. In order to induce a forced circulation of the cooling medium over the outside surfaces of the die, such outside surfaces may be provided with the curved ribs 22, which are analogous to the blades of a centrifugal pump. These blades 22 will pick up the cooling medium from near the axis of rotation of the die, and project it outwardly by centrifugal force, so causing a forced circulation of the cooling medium and a more reliable cooling effect. In order to further enhance this cooling effect, annular disk-like elements 23, supported by studs 24 mounted on the casing elements 4 and 5, are positioned slightly spaced from the outside surfaces of the die, and substantially parallel thereto. The inner parts of said disk-like elements 23 are cut away as at 23', to leave an opening between the edge of said cut away portion and the parts 15 and 9 of the die. The disk-like elements 23 accordingly define a definite channel for the passage of the cooling element over the outside surfaces of the die, the described ribs 22 forcing the cooling medium outwardly, resulting in more being taken in through the opening 23', and so providing a continuous circulation.

The funnel 13 is positioned within the portion 15 of the element 1, so as to be slightly spaced therefrom to leave a space 15' for the escape of gas from the space 16.

The operation of the device will now be apparent. The box 4 is filled with the desired cooling medium at the proper temperature, the die then speeded up to a high rate of speed, and the molten metal poured in through the funnel element 13; the metal passes into the space 16, and is immediately and powerfully thrown by centrifugal force 40 into the mold 3, where the centrifugal force will hold it as long as the rotation is kept up. Due to the high specific gravity of the molten mass, relative to any small bubbles of gas which may be present, the molten 45 mass will be thrown to the outside, and the bubbles of gas forced to the inside, thereby giving a dense casting, free from bubbles. When the parts are sufficiently cool, the parts are disassembled, the die taken apart 50 and the castings removed.

It should be understood that this invention is applicable to any form of casting, not only of metal, but of other materials that may be susceptible of casting, such as 55 bakelite.

While I have shown a possible embodiment of my invention, and have suggested possible steps in carrying it out, it should be understood that both the apparatus and 60 the method may be modified and carried out

in other ways, as defined within the scope of the appended claims.

I claim—

1. A casting apparatus, comprising die-forming means adapted to rotate at high speed, means for feeding a molten mass to said die-forming means, means to immerse said die-forming means in a cooling medium, said die-forming means being provided with means on the outside thereof to 70 pick up said cooling medium and cause a forced circulation thereof.

2. The combination as claimed in claim 1, in combination with means positioned in the cooling medium to define a path for the circulation of said cooling medium over the outside of said die-forming means.

3. A casting apparatus, comprising die-forming means adapted to rotate at high speed, means for feeding a molten mass to 80 said die-forming means, means to immerse said die-forming means in a cooling medium, and means positioned in the cooling medium to define a path for the circulation of said cooling medium over the outside of 90 said die-forming means.

4. In a centrifugal casting machine, the combination of a mold structure, supporting means for mounting the mold structure for rotation about a vertical axis, the mold 95 structure being so shaped and arranged as to provide, substantially concentric with the axis, an annular chamber formed by two converging walls, with the open side of the chamber directed toward said axis, and 100 means for confining a body of cooling liquid in contact with the exterior of the mold structure at all times.

5. In a centrifugal casting machine, the combination of a mold structure, supporting 105 means for mounting the mold structure for rotation about a vertical axis, the mold structure being so shaped and arranged as to provide, substantially concentric with the axis, an annular chamber formed by two 110 converging walls, with the open side of the chamber directed toward said axis, the upper surface of said mold structure within the bounds of the annular chamber being formed and arranged as an initial receptor, 115 and centrifugal projector for molten metal, and means for confining a body of cooling liquid in contact with the exterior of the mold structure at all times.

6. In a centrifugal casting machine, the 120 combination of a mold structure, supporting means for mounting the mold structure for rotation about a vertical axis, the mold structure being so shaped and arranged as to provide, substantially concentric with the 125 axis, an annular chamber formed by two converging walls, with the open side of the chamber directed toward said axis, the upper surface of said mold structure within the bounds of the annular chamber being 130

formed and arranged as an initial receptor, and centrifugal projector for molten metal, said receptor being formed as an upstanding protuberance substantially identical in all axial sections, and means for confining a body of cooling liquid in contact with the exterior of the mold structure at all times.

7. A casting apparatus, comprising die-forming means adapted to rotate at high speed about a vertical axis, means for feed-

ing molten metal to said die-forming means, a chamber around said die-forming means adapted to contain a cooling medium in contact with said die-forming means, said die-forming means being so shaped on the outer 15 surface thereof as to increase the cooling action of the medium employed.

In testimony whereof I affix my signature.

EARL H. SHERBONDY.
